UNITED STATES PATENT OFFICE

ELY C. HUTCHINSON, OF OAKLAND, CALIFORNIA, ASSIGNOR TO THE PELTON WATER WHEEL COMPANY, OF SAN FRANCISCO, CALIFORNIA, A CORPORATION OF CALIFORNIA

HYDRAULIC NEEDLE NOZZLE

Application filed March 17, 1928. Serial No. 262,491.

This invention relates generally to the construction of hydraulic needle nozzles, and particularly to the needle members employed in such devices.

5 In hydraulic installations, such as hydroelectric plants, it is common to utilize discharge nozzles having orifices controlled by adjustable needles. In order to secure high efficiency, the points of these needles must be 10 accurately shaped in accordance with well known hydraulic principles. In practice it has been found that the needle points and the correlated stationary portions of the nozzles are subject to wear and erosion. Such 15 wear may be due to a number of different causes, such as occurrence of abrasive materials or the presence of chemical substances in the water being discharged. Because of distortion of the needle points from their 20 true hydraulic form thru wear or erosion, prior needles have required frequent replacement in order to keep the nozzles operating at high efficiency. Loss in efficiency due to wear is particularly detrimental in large turbine installations or where comparatively 25 high water heads are employed.

It is an object of this invention to devise a needle construction for a needle nozzle which will resist wear and erosion, and which 30 will therefore maintain its operating efficiency over comparatively long periods.

It is a further object of this invention to devise a needle construction which will permit the use of wear resisting material for 35 the needle point without necessitating constructing the entire needle body of such material.

It is a further object of this invention to 40 devise a novel needle construction for hydraulic nozzles, which will have a replaceable wear resisting point.

Further objects of the invention will appear from the following description in which I have set forth the preferred embodiment of 45 my invention. It is to be understood that the appended claims are to be accorded a range of equivalents consistent with the state of the prior art.

Referring to the drawings:

50 Figure 1 is a side elevational view of a

needle constructed in accordance with my invention, a portion of the needle being shown in cross section.

Fig. 2 is a side elevational view in cross section of the needle point core utilized in 55 the construction shown in Fig. 1.

Fig. 3 is a side elevational view in cross section illustrating the wear resisting jacket for the core shown in Fig. 2.

Fig. 4 is a side elevational view in cross section illustrating the parts shown in Figs. 2 to 4 inclusive, in assembled relationship. 60

Fig. 5 is a cross sectional view taken along the line 5—5 of Fig. 4.

Fig. 6 is a general view illustrating the 65 complete hydraulic nozzle as applied for use with a hydraulic turbine.

As has been previously explained, hydraulic needle nozzles of the type to which this invention relates are generally constructed of a hollow tubular member 10 connected with a source of water under pressure, and having a discharge orifice 11 within which is disposed a needle 12. This needle is associated with mechanism well known in the 70 art whereby it can be adjusted longitudinally within the orifice 11, thus controlling the flow of water.

The detailed construction of the preferred embodiment of my invention is shown in 75 Figs. 1 to 6 inclusive. Referring to these figures the needle shown consists generally of

a body portion 14 and a point portion 16 secured to one end of the body portion. Extending from the other end of the body portion 14, is the usual needle stem 17. Body portion 14 and point portion 16 form what is termed the "bulb" of the needle, and the working portion of this bulb is formed by portion 16. In the past such needles have 80 been constructed in such a manner that it has been impracticable to employ wear resisting materials which would increase the life of the nozzle, due to both the cost of such materials and to the fact that they are difficult to machine. In my invention I make the point 16 out of some suitable wear resisting metal, while the body 14 and stem 17 are made of cheaper metal readily machinable 85 by ordinary tool processes. As substantial- 90

100

ly all of the wear of the nozzle takes place along the surface of the point 16, my construction is fully as effective in operation as a needle constructed entirely of expensive wear resisting material. Materials which will resist wear better than the usual readily machinable metals, are well known in the art. For example I may employ various metal alloys generally known as stainless steels or stainless irons, or I may employ chrome nickel alloys, manganese steel, acid resisting metals, and the like. As such materials are generally too hard to machine by ordinary processes or so hard as to make their machining expensive, there is an added advantage in limiting the use of this material to the point portion 16, in that I can utilize a readily machinable metal for the body portion 14 and stem 17.

20 In the preferred embodiment of my invention, the point portion 16 is made separable from the body 14, and the wear resisting material is preferably made in the form of a shell 18 which is secured to an inner core 19. 25 Core 19 is detachably secured to the body portion 14, as by means of an extension 21 from the stem 17, this extension projecting thru the body portion 14 and having threaded engagement 22 with the core 19. The shell 30 16 is preferably fixedly secured with respect to the core 19 so that the core and shell form a single unit which can be removably secured to the remainder of the needle.

35 As a suitable and preferable means for fixing the shell 16 to the core 19, I have shown the core 19 formed conical in shape, and having a plurality of peripheral grooves 23. These grooves are adapted to receive a plurality of spaced lugs 24 formed upon the 40 inner periphery of the shell 18. Slots 26 formed in the ribs between the grooves 23, make it possible to seat the jacket upon the core 19, after which the jacket may be rotated a fraction of a turn with respect to the 45 core in order to interlock the lugs 24 within grooves 23. I have also shown ribs or projecting portions 27 extending across grooves 23, in order to engage the lugs 24 and thus limit relative turning movement between the 50 jacket 16 and core 19. To facilitate aligning the core 19 with the jacket, I preferably provide the small end of core 19 with a conical projection 28 which is adapted to seat in an accurately positioned recess 29 formed within the jacket. After the core has been properly aligned with respect to the jacket, these 55 two parts are preferably fixed together by pouring molten zinc or other suitable metal 31 into the intervening spaces. The base portions of both the shell 16 and core 19, are preferably machined off so as to form a neat fit with the adjacent end portion of the body portion 14.

60 It is apparent that the needle construction described above will not only operate at a

relatively high efficiency over long periods, due to its wear resisting properties, but when replacement is necessary, it is sufficient to replace the point 16 rather than the entire needle construction. Only a small amount 70 of the hard expensive wear resisting metal is employed, and therefore the cost of my construction is not excessive. The machining of the shell 16 can be done by tool or grinding process, and during this operation I prefer 75 to retain the shell upon a mandrel similar to the core 19 described above. Since the body, stem and core are made of relatively soft metal compared to the shell, these parts can be machined without difficulty. 80

I claim:

1. In a hydraulic nozzle, a needle comprising a body member, a core detachably secured to said body, and a shell of wear resisting material surrounding and mounted upon 85 said core, said shell being formed to provide a tapered end portion for the needle.

2. In a hydraulic nozzle, a needle comprising a readily machinable metal core, a separate shell of wear resisting material surrounding the core, and cast metal disposed 90 between adjacent portions of said core and shell and serving to retain the same in interlocking engagement.

3. In a hydraulic nozzle, a needle comprising a body portion, a readily machinable metal core detachably secured to said body portion, a separate shell of wear resisting material surrounding the core, and cast metal disposed 100 between adjacent portions of said core and shell and serving to lock said shell to said core.

4. In a hydraulic nozzle, a needle comprising a body member, a readily machinable metal core detachably secured to one end of the body, a separate shell of wear resisting material surrounding the core, the outer periphery of said core and inner periphery of 105 said shell having portions capable of interlocking engagement.

5. In a hydraulic nozzle, a needle comprising a body portion, a core detachably secured to one end of said body portion, a separate shell of wear resisting material surrounding the core, the outer periphery of said core and the inner periphery of said shell having portions 115 capable of interlocking engagement, and means for retaining said portions in interlocking engagement.

6. In a hydraulic nozzle, a needle comprising a body member, a rod extending thru said member, a metal core detachably connected to one end of said rod, and a tapered shell or jacket surrounding and mounted upon said core, said jacket being made of material relatively more resistant to wear than the metal of the core.

7. In a hydraulic nozzle, a needle comprising a body member, a tapered core detachably secured to said body, and a shell of wear 120

130

resisting material surrounding and mounted upon said tapered core, said shell being formed to provide a tapered end portion for the needle.

- 5 8. In a hydraulic nozzle, a needle comprising a hollow body, a rod extending thru said body, a metal core member detachably connected to one end of said rod, and a tapered shell or jacket member surrounding or
10 mounted upon said core member, said jacket member being made of wear resisting material differing from the metal of the core member, projecting portions formed upon a peripheral portion of one of said members
15 adapted to cooperate with complementary grooves formed in the adjacent peripheral portion of the other of said members, and cast metal disposed between said members serving to securely fix the shell to the core.
- 20 9. In a hydraulic nozzle, a needle having an enlargement or bulb thereon, the forward working portion of the bulb comprising a core and a shell surrounding and mounted upon the core, the shell being of a material
25 having substantially better wear resisting properties than the material of the remaining portion of the bulb.
10. In a hydraulic nozzle, a needle comprising a body portion and a point portion, said point portion comprising a core and a wear resisting shell surrounding and mounted upon said core, and means for detachably securing said core to said body portion.

In testimony whereof, I have hereunto set
25 my hand.

ELY C. HUTCHINSON.
